UNITED STATES PATENT OFFICE

SAM EDWARD SPENCER, OF ELLAND, ENGLAND

GRID FOR GAS PURIFIERS

Application filed September 21, 1925, Serial No. 57,785, and in Great Britain October 22, 1924.

This invention relates to flat or horizontal grids for gas purifiers of the type wherein a row of support bars are arranged upon opposite sides of the bearer bars, with the bars in 5 one row breaking joint with the bars in the other rows; and has for its object the improved construction of such grids and arrangement of the aforesaid support bars, whereby comparatively large pockets are 10 formed upon one side of the grid in which the purifying material entering same builds up in a uniform minimum density, and upon the opposite side of the grid corresponding inverted cavities or spaces into which the 15 gases filtering through the layer of purifying material below congregate and are distributed uniformly to the layer above by way of the loose porous material in the pockets aforesaid.

A number of grids are employed to support 20 each layer of purifying material within a purifier, and in constructing my improved grid I arrange the support bars in each row in pairs with the space between each pair differing in width from the space between any 25 two pairs of said bars, and each pair of bars in one row breaking joint with the pairs of bars in the other row. The bearer bars may be of any suitable length and depth, they may be arranged back to back with the support bars 30 secured thereto upon one side only, or the support bars may be secured to opposite sides of said bars and the latter arranged side by side, in each instance the shape or arrangement, or both, of these support bars and 35 bearer bars provide grids in which the support bars in pairs break joint and pockets and cavities alternate upon both sides thereof, for the purposes aforesaid.

I attain these objects by the means illustrated in the accompanying drawings, in which:

Figs. 1, 2 and 3 are end, side, and plan views respectively, of one half or section of the bearer bar employed in the construction of 45 one form of my improved grid.

Figs. 4 and 5 are end view and plan of the support bar employed in conjunction with bearer bars illustrated at Figs. 1, 2 and 3.

Fig. 6 is an end view of the parts shown at 50 Figs. 1, 2, 3, 4 and 5 assembled.

Fig. 7 is an end view.

Fig. 8 is a side view.

Fig. 9 is a similar view to Fig. 7, showing the pockets containing purifying material, and the cavities or spaces for distributing the 55 gases filtering from one layer of said material to another.

Figs. 10 and 11 are end and side views respectively of a bearer bar employed in constructing my improved grid showing a modification in the shape of the recesses receiving the support bars.

Fig. 12 is an end view of my improved grid showing a modification of the shape in cross-section of the support bars employed therein 60 and of the recesses in the bearer bars to receive them.

Fig. 13 is an elevation of the type of screw-nail employed in securing the support bars to the bearer bars.

Figs. 14 and 15 are end view of my complete grid, showing a modification in the length of the bearer bars, and in Fig. 15, in the arrangement of the latter whereby the superimposed bearer bars also break joint.

Fig. 16 is an end view of my improved grid with short length bearer bars and a modification in the shape and arrangement of the support bars thereon.

Figs. 17 and 18 are end and side views respectively of a further modification of my improved grid embodying short length bearer bars, and the method of securing the support bars thereto.

Figs. 19, 20, 21 and 22, are further modifications in the shape or length of the support bars and bearer bars, and in the method of securing the former to the latter.

Figs. 23 and 24 are end views of further modifications.

Similar letters refer to similar parts throughout the several views.

Referring to Figs. 1 to 9. A are support bars of any suitable length, rhomboidal in shape in cross-section and arranged in parallel pairs upon one side of bearer bars B, the distance between each pair of bars A being comparatively much less than that between any two pairs of such bars. The bars B are suitably recessed at C to receive the bars A. 100

and support the same near each end of the latter but where said bars A are of more than average length, one or more intermediate bars B may be employed. Suitable 5 nails D secure the parts A, B, together and a small portion of bitumen, or a material sold under the registered trade mark "Ave-bene", or other similar material E, is placed in the bottom of the recesses C, (see Fig. 2), 10 which during the nailing operation becomes flattened out, surrounding the nail connection, protecting same from corrosion, and rendering the joint gas tight at this part.

Two of the above-described sections go to 15 make a complete grid by being arranged with the bars B back to back, (see Fig. 7), the pairs of bars A being arranged in the latter so that upon assembly as aforesaid, the pairs of bars in one row break joint with 20 the pairs of bars in the other row for the purposes aforesaid. F is a dowel or projection secured to one of the bars B and normally, loosely fits a corresponding recess in the other bar B of each grid to prevent one 25 or the other of these sections relatively shifting their positions after being laid in the purifier.

By this construction of grid, (see Figs. 7 and 9), pockets G are formed therein between 30 each two pairs of bars A in the upper row, and terminating between each pair of bars A in the bottom row, the sides of these bars assisting the purifying material to build up in a loose porous condition and prevent its 35 escape to the layer below. Correspondingly shaped pockets or cavities H on the under-side of the grid, alternate with the pockets G and give access to the gases filtering through the layer of material below, which are thereby distributed to the said pockets G uniformly 40 throughout the whole area of the purifier, resulting in maximum filtration of the gases passing through the same and the maintenance of a uniform density of the purifying 45 material throughout. The shape of the support bars and the corresponding recesses in the bearer bars demonstrate when the two sections are secured together, a grid of exceptional stability and strength.

50 With reference to Figs. 10 to 15, these show modifications of my improved grid more particularly regarding the shape in cross-section of the support bars A, the manner of and means for securing the said bars 55 to the bars B, and in the length of the latter. Where the bars A are rectangular in shape the opposing sides of each pair are parallel, and the space between of a uniform narrow width, which ordinarily would similarly affect and weaken the rib J formed in the bars B were the bars A to be similarly recessed therein. To strengthen this rib I form a suitable rebate K in the said opposing sides of the bars A where they engage 60 the bars B, which correspondingly widens

and strengthens the said rib J, (see Fig. 12), as desired. To secure the bars A to the bars B, I form holes or recesses L in both, into which are driven screw-nails D of the kind shown at Fig. 13, of slightly larger diameter; the pitch of these nails is such as to cause them to rotate or turn when being driven into the bars, and form a corresponding thread within the recesses L aforesaid which prevents the bars from working loose or becoming detached. Where required to make the grids square with the sides of the purifier, I employ a short length bearer bar B¹ containing a single support bar A¹ (see Fig. 15).

With reference to Figs. 16 to 24, these views illustrate further modifications in the construction of my improved grid, and are mainly subdivisions of the grids shown at Figs. 14 and 15, or, in which different shapes of bars A and B are employed, or in the relative arrangement thereof, and in the means for securing the said bars together to form the grid. In some cases dowels N are passed through both bars A and B, and are prevented from shifting their positions by nails D driven through both the dowel N and the bar A.

What I claim as my invention, and desire to secure by Letters Patent is:—

1. A grid for gas purifiers comprising carrying means, support members rhomboidal in cross-section arranged in rows above and below said means and engaged therewith, the members of each row being arranged in pairs with the spaces between the members of each pair differing in width from the spaces between adjacent pairs, the pairs of support members in one row positioned to break joint with the pairs of members in the other row, the said support members forming alternate pockets for the reception of purifying material and the passage of gas.

2. A grid for gas purifiers comprising bearer bars, support members rhomboidal in cross-section arranged in rows and secured upon opposite sides of said bearer bars with the bearer bars secured to each other, the rows of supporting members being arranged in pairs with the spaces between the members of each pair less than the space between adjacent pairs, the pairs of support members upon the upper side of the bearer members positioned to break joint with the support members on the lower side of said bearer bars to form pockets containing purifying material supported by the lower row of members alternately with corresponding spaces for distributing gas to the purifying material, the said pockets being triangular in cross section with the confronting walls of the support members in alignment.

3. A grid for gas purifiers comprising pairs of superposed detachably associated bearer bars, support members arranged in rows

above and below said bars and secured thereto, the members of each row being arranged in pairs with the spaces between the members of each pair differing in width from the spaces between adjacent pairs, the pairs of support members in one row positioned to break joint with the pairs of members in the other row, the said support members forming alternate pockets for the reception of purifying material and the passage of gas.

4. A grid for gas purifiers comprising detachably associated carrying means arranged back to back, support members arranged in pairs with the space between the members of each pair differing in width from the space between adjacent pairs, a row of said support members being secured to opposite sides of the carrying means, the pairs of said members in one row positioned to break joint with the pairs of members in the opposite row.

5. A grid for gas purifiers comprising detachably associated carrying means arranged back to back, support members rhomboidal in cross section arranged in pairs with the space between the members of each pair differing in width from the space between adjacent pairs, a row of said support members being secured to opposite sides of the carrying means, the pairs of said members in one row positioned to break joint with the pairs of members in the opposite row.

In testimony whereof I have signed my name to this specification.

35 SAM EDWARD SPENCER.
